UNITED STATES PATENT OFFICE

ALEXANDER MCLEAN NICOLSON, OF NEW YORK, N. Y., ASSIGNOR, BY MESNE ASSIGNMENTS, TO WIRED RADIO, INC., OF NEW YORK, N. Y., A CORPORATION OF DELAWARE

PRODUCTION OF OSCILLATIONS FROM PIEZO ELECTRIC CRYSTALS

Application filed January 24, 1927. Serial No. 163,273.

My invention relates broadly to a system for the production of electrical oscillations and more particularly to a circuit arrangement for the generation of oscillations derived from piezo electric crystal elements.

One of the objects of my invention is to provide a system for generating oscillations by a piezo electric crystal controlled generator system whereby oscillations of a frequency lower than the natural frequencies of the piezo electric elements may be derived.

Another object of my invention is to provide a system for the production of differential beats or a third frequency from a piezo electric crystal controlled generator system where the differential beats may have a frequency within the audible range.

Another object of my invention is to provide a piezo electric crystal controlled generator system by which oscillations within the audible frequency range may be derived without the employment of cumbersome piezo electric crystal devices with all the inherent difficulties in the preparation of piezo electric crystals of large size.

A further object of my invention is to provide a piezo electric crystal controlled generator system in which a plurality of piezo electric crystal elements, each arranged to vibrate in a plurality of modes are connected with resonant circuits arranged to sustain oscillations at the natural frequency possessed by the piezo electric crystal elements for combining the effects thereof for the production of a frequency within the audible range.

Another object of my invention is to provide a piezo electric generator system wherein piezo electric crystal elements each adapted to vibrate in a plurality of modes and at a plurality of different frequencies are provided where the piezo electric crystal elements may be variably loaded for selectively adjusting the frequencies which are sustained by the associated electrical circuits.

Still another object of the invention is to provide a circuit arrangement for simultaneously controlling the frequency of a plurality of oscillations of different frequencies by means of piezo electric frequency controlled

devices, each arranged to vibrate in a plurality of modes.

My invention will be more clearly understood from the specification hereinafter following by reference to the accompanying drawing, in which: Figure 1, shows the circuit arrangement of the piezo electric crystal elements in association with an electron tube circuit arranged in accordance with the principle of my invention; Fig. 2, shows a mounting for the piezo electric crystal elements as employed in the oscillator system of my invention and Figure 3, is a plan view of the piezo electric crystal apparatus employed in the generator circuits of my invention.

My invention contemplates the production of oscillations within the audible frequency range by means of piezo electric crystal elements without the necessity of employing piezo electric crystal elements of cumbersome size. Under certain conditions it has been impractical to generate oscillations within the audible frequency range by reason of the large physical size of the piezo electric crystal element having a natural frequency corresponding to an audible frequency. By the circuit arrangement of my invention, I provide piezo electric crystal elements, each capable of vibration in a plurality of different modes and at a plurality of different frequencies, the piezo electric crystal elements being selected with respect to their natural frequencies for the derivation of differential beats or third frequency proportioned to the principal frequencies. This beat or third frequency may be within the audible range or the third frequency may be above the audible range dependent upon the natural frequencies of the piezo electric crystal elements. For the purpose of explaining my invention, I have illustrated the same as employing piezo electric crystal elements possessing the property of torsional vibration. At the same time that the piezo electric crystal elements are vibrating under conditions of torsion, the elements may be generating natural frequencies along the thickness dimension of the crystals or along the lateral or longitudinal axes of the crystal.

The circuits in which the piezo electric crys-

tal elements are included are provided with a plurality of resonant circuits for sustaining oscillations of selected frequencies. An electron tube system is provided to which the several resonant circuits are connected and by which the several generated frequencies may be combined to produce by their sum or difference, a frequency which may be ultimately delivered to a circuit common to the several circuits of the oscillator system. In order to minutely adjust the relation of the several frequencies which are impressed upon the electron tube oscillator circuits I provide means for mounting the piezo electric crystal elements in such manner that the piezo electric crystal elements may be subjected to conditions of variable loading through a mechanically coupled system. By mechanically coupling the piezo electric crystal elements, which are electrically connected in different resonant circuits associated with the input and output circuits of an electron tube system, there is provided an oscillatory system by which a differential beat frequency may be derived and slightly varied in a positive or negative direction by a variation in the loading producing a change in the natural period of vibration of the mechanical coupling between the piezo electric crystal elements. The differential frequency thus produced, may be employed for a variety of purposes. The ease of control of such frequencies and the fixing of the frequency at a constant value render the system of my invention adaptable for many types of control circuits where a constant frequency source is of extreme importance.

Referring to the drawing in more detail, reference character 1 designates an electron tube having a cathode or filament electrode 1a, grid electrode 1b and plate electrode 1c. Input circuit 2 connects across the grid and filament electrodes and an output circuit 3 connects across the plate and filament electrodes.

The input circuit 2 includes an inductance system 4 while the output circuit 3 includes inductance system 5 and the high potential source 6. The cathode of filament electrode 1a is heated from battery 7. The input and output circuits are interlinked by means of the frequency determining circuits which constitute an important part of my invention. I have illustrated sets of piezo electric crystal elements represented more clearly in Figs. 2 and 3 which are connected in resonant circuits which are in turn coupled to the input and output circuits of the oscillator. I have shown piezo electric crystal elements 19 and 20 mechanically coupled by means of an extremely light coupling member 23. Each piezo electric crystal element is free to vibrate by reason of a special mounting such as of sponge rubber 28 and 29 or glass wool carried in standards 26 and 27. Piezo electric

crystal element 19 is provided with electrodes 19a and 19b.

The piezo electric element 20 is provided with electrodes 20a and 20b which provide electric terminals for each of the piezo electric crystal elements. The linkage 23 provided with the laterally extending strut 25 carries a movable mass represented by screw threaded nuts 24 and by changing the position of this mass, a change in the rate of vibration of the piezo electric crystal system may be effected.

The piezo electric crystal system constituted by piezo electric crystal elements 10 and 11 is similarly arranged. That is, piezo electric crystal 10 has terminal electrodes 10a and 10b while piezo electric crystal element 11 has terminal electrodes 11a and 11b. The mechanical linkage or coupling 12 between the piezo electric crystal elements is provided with a laterally extended strut 13 on which the mass 14 is variably adjustable. The adjustment of the mass 14 or 24 on the struts 13 and 25 respectively causes changes in the natural frequency of the system.

Connected across the electrodes of each piezo electric crystal element, I provide circuits which may be made resonant to the natural frequency of the piezo electric crystal element in any selected mode thereof. Across the piezo electric crystal element 10, I provide a resonant circuit constituted by inductance 8 and variable capacity 9. The inductance 8 is variably coupled to inductance 4 in the input circuit 2. Piezo electric crystal element 19 has its opposite terminals connected across a resonant circuit constituted by inductance 17 and variable condenser 18. The inductance 17 is variably coupled to inductance 4 in the input circuit 2.

The piezo electric crystal element 20 has its terminals connected across inductance 22 and variable condenser 21 where the inductance 22 is variably coupled with the inductance 5 in the output circuit 3 of the electron tube 1. In a similar manner, piezo electric crystal element 11 has its terminals connected to a resonant circuit including inductance 15 and variable condenser 16, where the inductance 15 is variably coupled with the inductance 5 in the output circuit 3. By choosing the nature and dimensions of the piezo electric crystal elements and the mechanical coupling, the natural frequencies thereof may be so combined through the coupling with the input and output circuits of the electron tube 1 as to derive oscillations of a frequency within the audible range, if desired, which are transferred to inductance 31 of an output circuit 32. The several independent frequencies are inter-modulated in the electron tube circuits so that the resulting frequency may be the sum or difference of the frequencies originally impressed upon the electron tube circuits from the resonant

circuits. There may be oscillations at a plurality of natural frequencies impressed upon the electron tube circuits for the development of the desired constant frequency which is supplied to the output circuit. By adjustment of the periodicities of the several resonant circuits, the combined effects of the natural oscillations in any desired mode from the piezo electric crystal elements may be integrated in the electron tube circuits.

While I have illustrated one preferred embodiment of my invention, I desire that it be understood that modifications may be made and that no limitations upon my invention are intended other than are imposed by the scope of the appended claims.

What I claim as new and desire to secure by Letters Patent of the United States is as follows:

1. An oscillation generator comprising means for generating a plurality of different frequency oscillations, a piezo electric device having a plurality of crystal elements traversed by said oscillations and vibrating at a plurality of natural frequencies corresponding to the frequency of each of said oscillations, and means mechanically linking the crystal elements of said device for crystal-stressing to modify the frequency of the oscillations developed by said piezo electric device.

2. In an oscillation generator, a space discharge device, a circuit so associated with said device that oscillations of a plurality of frequencies are generated therein, means comprising a piezo electric device having a plurality of crystals and a resonant circuit for simultaneously determining the frequency of all of said oscillations and means including a linkage member between said crystals for variably stressing said piezo electric device for fixing the frequency at which said device sustains oscillations.

3. In a space discharge tube system a three-electrode space discharge tube, input and output circuits for said tube, said circuits being coupled to produce continuous oscillations of a plurality of frequencies, a piezo electric device including a plurality of crystals for maintaining the frequency of said oscillations constant, and means including a weighted member interconnecting said crystals for mechanically and adjustably stressing said piezo electric device for changing the periodicity of said device.

4. In an oscillation generating system a space discharge tube, a piezo electric device having a pair of crystals, a circuit including said tube and said device having generated therein a plurality of continuous waves of frequencies above audibility, means for obtaining from said waves a wave of audible frequency, and means mechanically interconnecting said crystals for distorting said piezo electric device under stress of mechani-

cal forces for adjusting the control of said audible frequency wave as to frequency by said piezo electric device.

5. An oscillation generator comprising a space discharge tube, means coupling the input and output circuits of said space discharge tube, a piezo electric crystal device, said piezo electric crystal device being divided into two portions mechanically coupled one to the other, a resonant circuit connected across each portion of said piezo electric crystal device said resonant circuits being coupled to the input and output circuits of said space discharge tube, said piezo electric device operating to determine the frequency of the circuits of said space discharge tube.

6. In an oscillation generator system comprising an electron tube having input and output circuits, inductances interposed in each of said circuits and a plurality of piezo electric crystals adapted to be mechanically and adjustably distorted, a weighted member cooperating with said crystals to mechanically interconnect the same, each said crystal connected in separate resonant circuits, each of said resonant circuits coupled with the inductances in said circuits whereby a differential frequency is produced in said circuits.

7. An oscillation generator system comprising an electron tube having grid, filament and plate electrodes, input and output circuits interconnecting said electrodes, inductances interposed in each of said circuits, a pair of piezo electric crystals adapted to be mechanically and adjustably distorted, a link member mechanically coupling said crystals together, a resonant circuit connected across each of said piezo electric crystals, the resonant circuits of each of said piezo electric crystals being electrically coupled with the inductances in said input and output circuits, respectively, for the production of oscillations of a differential frequency with respect to the oscillations of each of said piezo electric crystal elements.

8. A wave generator system comprising a plurality of resonant circuits including piezo-electric elements for sustaining oscillations of selected frequencies, an electron tube oscillator circuit system coupled to the several resonant circuits for combining the several generated frequencies, an audio frequency circuit responsive to said electron tube system, each of said piezo elements being adapted to vibrate in a plurality of modes and at a plurality of different frequencies and being selected with respect to their frequency characteristics for the derivation of differential beats proportioned to said frequencies, and means mechanically interconnecting said piezo elements for variably mechanically distorting the same for selectively adjusting the relation of the several frequencies impressed upon said electron tube oscillator circuit.

9. An oscillator comprising a space-discharge tube, input and output circuits for said tube each including an inductance system, a plurality of frequency-determining circuits coupled to said inductance systems, said frequency-determining circuits including resonant circuits coupled to said input and output circuits and flexibly mounted sets of piezo-electric crystal elements connected in said resonant circuits, said sets having a plurality of piezo elements mechanically coupled by an extremely light coupling member having an adjustable weight or mass for adjusting the vibration periods of the piezo sets by flexing or bending the individual piezo plates.

10. An oscillator comprising a space-discharge tube, input and output circuits for said tube each including an inductance system, a plurality of frequency-determining circuits coupled to said inductance systems, said frequency-determining circuits including resonant circuits coupled to said input and output circuits and flexibly mounted sets of piezo-electric crystal elements connected in said resonant circuits, said sets having a plurality of piezo elements mechanically coupled by an extremely light coupling member having an adjustable weight or mass for adjusting the internal stresses in said piezo elements and the consequent vibration periods thereof.

11. A resonator comprising an oscillation circuit, a frequency-determining system for said oscillation circuit, said frequency-determining system including adjustable frequency piezo-electric apparatus comprising a plurality of crystals flexibly mounted and mechanically connected by non-piezo electric material, said material including an adjustable weight for varying the tension and compression forces on said crystals and simultaneously varying their frequency characteristics.

12. A resonator comprising an oscillation circuit, a frequency-determining system for said oscillation circuit, said frequency-determining system having adjustable frequency piezo-electric apparatus including a device having piezo-electric properties and loading means for bending said device to adjustably vary its frequency characteristics.

13. A resonator comprising an oscillation circuit, a frequency-determining system for said oscillation circuit, said frequency-determining system having adjustable frequency piezo-electric apparatus including a plurality of crystals and loading means mechanically and adjustably interconnecting said crystals for bending the same to adjustably vary their frequency characteristics.

14. A resonator comprising an oscillation circuit, a frequency-determining system for said oscillation circuit, said frequency-determining system having adjustable frequency

piezo-electric apparatus including a plurality of crystals and loading means mechanically and adjustably interconnecting said crystals for bending the same to adjustably vary their frequency characteristics, said loading means being operable independently and irrespective of its elastic properties, its natural period of vibration and of its temperature changes, and being of relatively light weight with respect to the weight of its associated crystal.

In testimony whereof I affix my signature.
